BAR FEED MEANS

George O. Gridley, Berlin, Conn., assignor to The
New Britain Machine Company, New Britain,
Conn., a corporation of Connecticut

Application December 20, 1947, Serial No. 793,013

7 Claims. (Cl. 29—59)

1

My invention relates to automatic machines, and in particular to automatic stock-feeding mechanisms for bar machines.

It is an object of the invention to provide an improved mechanism of the character indicated.

It is another object to provide an improved stock-feeding mechanism employing hydraulic actuating means.

It is a more specific object to provide a hydraulically actuated mechanism of the character indicated, wherein the desired feeding strokes may be effected by a more compact and less cumbersome structure.

It is another object to provide a hydraulically actuated mechanism of the character indicated, wherein a given stock-feed stroke may be adjustably selected so as to obviate the need for the stock stop.

Other objects and various further features of the invention will be pointed out or will occur to those skilled in the art from a reading of the following specification in conjunction with the accompanying drawings. In said drawings:

Fig. 1 is a simplified side view of an automatic lathe to which a stock-feed mechanism according to the invention has been applied;

Fig. 2 is an enlarged sectional view taken substantially in the plane 2—2 of Fig. 1;

Fig. 3 is a sectional view taken substantially in the plane 3—3 of Fig. 2;

Fig. 4 is a schematic arrangement of hydraulic actuating circuits for the mechanism of Fig. 1;

Fig. 5 is a view similar to Fig. 1, but illustrating a modified construction;

Fig. 6 is a sectional view taken substantially in the plane 6—6 of Fig. 5;

Fig. 7 is another view similar to Fig. 1 to illustrate a still further modification of the invention;

Fig. 8 is an enlarged detailed view of a portion of the mechanism of Fig. 7; and

Fig. 9 is a sectional view taken in the plane 9—9 of Fig. 8.

Briefly stated, my invention contemplates an improved stock-feeding mechanism that may be employed periodically to feed out tubular or bar stock, say, through the collet or chuck of an automatic lathe. Fluid-pressure actuating means propel the stock substantially for the feed-out distance before recycling for the next feed-out operation. In the forms to be described, the pressure actuating means is hydraulic and drives a drum or winch over which a cable is payed for attachment to the feed carriage. Various mechanisms are shown for engaging the hydraulic actuating means to the drum, and in one form

2

the feed stroke may be adjustably selected without modifying the stroke of the hydraulic actuating means.

Referring to Figs. 1 through 4, my invention is shown in application to a stock-feeding mechanism for an automatic lathe 10 having a spindle 11 revolubly to support tubular or bar stock 12, as in an internally fed collet or chuck 13. The stock-feed mechanism may include a feed carriage 14 slidable in longitudinally extending ways in a frame 15 at the rear end of the automatic lathe 10. The carriage 14 may incorporate a longitudinally adjustable abutment member 16, having a centering nose 17 for the case of the tubular stock 12 shown. The centering nose 17 is preferably freely rotatable with respect to the abutment member 16 so as to provide effective support for the rearwardly projecting end of stock 12.

In accordance with the invention, hydraulic actuating means are employed periodically to advance the stock 12 to a new feed-out position when lathe operations have been completed on the previously fed-out stock. A limiting feed-out position may be determined by a stock stop 18. In the form shown, hydraulic actuation for the stock-feed mechanism is derived from the motion of a piston 19 traveling in a cylinder 20 fixed relatively to the frame 15. The motion of piston 19 may be employed to drive a drum 21 carrying a cable 22 attached at one end, as at 23, to the feed carriage 14. The piston rod 24 for the hydraulic actuating means may carry a rack 25 which may slide in ways 26, so as to be positioned for driving engagement with a gear 27 for driving the drum 21.

One-way-engaging ratchet means 28 may be provided between the gear 27 and the drum 21 to permit the drum 21 to overrun the gear 27 (if possible) or to permit recycling of the piston 19 for again driving the gear 27. In the form shown, the gear 27 is keyed at 29 to the hub of driving member 30 of the ratchet mechanism 28. The driven part of the ratchet mechanism 28 may be formed integrally with the drum 21, as by providing the drum 21 with a bore 31. For set-up purposes, the drum 21 may be keyed, as at 32, to a supporting shaft 33 having at one end a projection with flats 34 to be engaged as by a crank. The ratchet mechanism 28 may include one or more slidably pawl members 35, which are shown as rollers. The rollers 35 may be spring urged for wedging contact between the bore 31 and flats 36; the flats 36 may be milled in the driving member 30 of the ratchet mechanism 28.

In accordance with a feature of the invention, I provide means whereby in addition to the positive driving action of the hydraulic actuating means upon the drum 21 there may be a substantially constant further feed force applied through cable 22 to the feed carriage 23. In the form shown, this further force is derived from a weight 37 attached to the other end of the cable 22 and suspended as over an elevated pulley 38. The pulley 38 may be located above the machine, or a hole 10 (not shown) in the shop floor may provide clearance for the full travel of the weight 37. It will be clear that if the cable 22 is wound a number of times over the drum 21 (see Fig. 2), the weight 37 may perform the dual function of applying a 15 constant feed force to the carriage 14 and of assuring an adequate cable grip upon the drum 21, so that hydraulic actuation of drum 21 may be effective to feed even the heaviest stock 12.

In the preferred arrangement shown, the working stroke of the piston 19 is at least sufficiently long to permit a full feed-out of stock 12 to a stock stop 18, without requiring further hydraulic feed strokes. If the stock stop 18 should be placed relatively close to the chuck 13, as when short pieces of work are to be formed on the lathe, then it will be clear that the nature of cable engagement with the drum will permit cable slip action once the stock 12 has hit the stock stop 18. This slip action will be characterized by a full stroke of piston 19 and by a correspondingly complete arcuate advance of the drum 21; at the same time, the amount of cable advance may only be relatively small, as determined by the position of stock stop 18.

Referring to Fig. 4, I illustrate schematically a method of automatically recycling the hydraulic actuating means 19. In Fig. 4, the work 12 will be recognized as held by the drawback chuck or collet 13, which in turn is seated in and revolvably supported by the spindle 11. Actuation of the drawback collet 13 may be effected through a collet tube 13', supporting at its rear end an actuating spool 39 having an annular groove 40 to be engaged as by a fork 41. In the form shown, the fork 41 is supported on a sliding bar 42 and carries at one end a cam-follower roll 43 to engage the cam slot in a drum cam 44, which may be on the cam shaft of the lathe 10.

The sliding bar 42 on which the fork 41 is mounted may also be employed to position the crank 45 of a control valve 46 for reversibly actuating the piston 19. In a first position of the valve 46, a first passage 47 connects a source 48 of hydraulic pressure through line 49 to the head end of the cylinder 20 so as to actuate piston 19 from left to right. This will be recognized as a retracting stroke wherein the ratchet mechanism 28 does not engage and wherein, therefore, no motion is imparted to drum 21 or to the carriage 14. During this retraction stroke of the piston 19 exhaust fluid is expelled from the tail end of the cylinder 20 through a pipe 52 to a second passage 50 in the valve 46, for conduct to a sump 51. The described retraction stroke will be appreciated as occurring at the beginning of the relatively long dwell on cam 44; piston 19 will remain so retracted for the duration of the dwell, as will be clear.

In the second position of valve 46, as when the follower 43 is in the relatively short rise of cam 44 (i. e. when the collet is open), the passage 47 directs pressurized fluid to the tail end of cylinder 20 to drive the piston 19 from right to left. In this second stroke the ratchet mechanism 28 will

be understood to engage, so that stock-feeding motion will be imparted by the hydraulic actuating mechanism to the drum 21, and hence to the carriage 14. During this second or feed stroke, 5 exhaust fluid from the head end of cylinder 20 will be directed through the exhaust passage 50 in valve 46, for discharge into the sump 51.

It will be appreciated that since the valve 46 is directly actuated by the mechanism which also actuates the collet 13, the necessary stock feed forces may be applied to advance stock 12 only when the collet 13 is open. When the cam follower 43 again rides in the dwell on cam 44, the valve 46 is positioned to reset the hydraulic actuating cylinder 20 and its piston 19 for the next feed stroke. It will be recalled that throughout the described cycle of events the weight 37 will have been effective at all times to assure some load in a feeding direction on the carriage 14 and that 20 such load may at least have been effective to provide adequate support for the projecting and otherwise unsupported back end of stock 12.

In Figs. 5 and 6, I show a modified form of the invention in which hydraulic actuating means 25 drive feed carriage 14 through another type of ratchet engagement. Much of the structure of Fig. 5 will be recognized from Fig. 1, that is, the carriage 14 may be slidable along a frame 15 and support stock 12 for feeding through the back 30 end of an internally fed chuck 13 in an automatic lathe 10. A stock stop 18 may serve to determine limiting advances of the fed-out stock 12. The hydraulic actuating means again may include a piston 19 slidable in a cylinder 20 and driving a 35 rack 25 slidable in ways 26. The rack 25 may drive gear 54, and ratchet means 55 may impart the motion of gear 54 at least in one direction to a cable drum 56. The cable 57 on the drum 56 is prefer-fastened thereto at one end, as at 58, and 40 at the other end to the feed carriage 14, as at 59. In the form shown, the ratchet mechanism includes a pawl 60 carried by the drive gear 54 and positioned for one-way engagement with a ratchet wheel 61 of the ratchet mechanism 55. The 45 ratchet wheel 61 may be formed with the drum 56 or locked thereto, as by key means 62.

It will be appreciated that in Fig. 5 the working stroke of the hydraulic actuating means 19 may be in the same direction as that shown in Fig. 1. 50 In other words, feed motion may be imparted to the drum 56 and hence to the feed carriage 14 upon a right-to-left displacement of piston 19. In this displacement the pawl 60 may be carried by gear 54 in a single positive engagement with 55 the ratchet wheel 61 so as further to wind cable 57 on the drum 56. Upon retraction (left to right) of the piston 19, the pawl 60 will be allowed to escape a number of teeth of the ratchet wheel 61 and this number will depend upon the 60 extent to which the stock stop 18 permitted a feed of new stock 12. During retraction of piston 19 and until the hydraulic actuating mechanism is again energized to feed the stock, holding forces may be continuously applied to the stock 12 by means of a holding ratchet 63, backing up the ratchet means 60. The ratchet 63 may be effective to lock drum 56 to the frame except when the chuck 13 is open and feeding forces are being applied.

The arrangement of Figs. 5 and 6 will be appreciated as providing for a relatively positive application of feed forces to the feed carriage 14. When a feed stroke is limited by abutment of the stop 12 with the stock stop 18, the motion of piston 19 will be momentarily arrested, and the

fastening pawl 63 will serve to hold the cable taut in this fed-out position. Reclamping of the collet 13 will be accompanied by a return of the piston 19 to the position shown, while the pawl 63 may retain the strong feed-out forces in their application to the rear end of the stock 12.

In Figs. 7, 8, and 9, I show still another modification of the invention, wherein the stroke of the hydraulic actuating mechanism may be adjustably selected so as to obviate the need for the stock stop 18 of the above-described mechanisms. The arrangement of Figs. 7, 8, and 9 will be recognized as being applicable to an automatic lathe 10 having an internally fed collet or chuck 13 for holding stock 12 in position to be turned in a spindle 11. The rear end of the stock 12 may be fed and supported by the centering piece 17 of an adjustable bar 16 carried by a feed carriage 14, and the feed carriage 14 may be slideable in a frame 15. Hydraulic actuating forces may again be derived from the working stroke of a piston 19 to drive a drum 65 supporting a cable 66, which in turn may be attached at one end to the feed carriage 14, as at 67.

The drum 65 may receive its feed motion from a gear 68 having a portion to cooperate with ratchet means 69. The ratchet means 69 may include a sliding pawl similar to those described in Fig. 3. In the form shown, the gear 68 is engaged by a sector gear 70 keyed to a crank 71, and the crank 71 is thrown by a link 72 directly connected to the piston rod 21, as at a cross-head 73 traveling in guides 74.

In accordance with the invention, the link 72 may be attached at adjustably selected points on the crank 71, as determined by the position of a block 75 in a slot 76. It will be appreciated that with the mechanism described a right-to-left stroke of the piston 19 may cause positive engagement of the ratchet 69 so as to drive drum 65 clockwise (in a winding direction), to feed the carriage 14 and hence the stock 12. If the adjustable block 75 has been properly set for a desired feed-out advance of the stock 12, then there may be no need for a stock stop, and a full stroke of the piston 19 may accomplish a full feed-out advance of stock 12. As in the case of Fig. 4, a clamping of the collet 13 may be accompanied by a recycling or left-to-right return of piston 19 into position for another feed-out stroke. During this return stroke, another one-way engaging ratchet mechanism 77 between the drum 65 and the frame 78 will be understood to hold the cable 66 and thus adequately to support the tail end of the stock 12.

It will be appreciated that I have described relatively simple stock-feed mechanisms which, compared with existing structures, may be small, compact, and efficient. In all cases, there need be no danger of overstressing the mechanism, even when fed-out stock is arrested by a stock stop. Furthermore, in all cases provision may be made for assuring a constant application of force in a feeding direction so as to support the rear end of stock even when the actuating mechanism is being recycled. In the preferred form wherein relatively incompressible fluids are employed, the action of my stock-feed mechanism will be understood to be smooth, positive, and accompanied by no "bouncing" of the stock.

While I have described my invention in detail for the preferred forms shown, it will be understood that modifications may be made within the scope of the invention as defined in the appended claims.

I claim:

1. In a machine of the character indicated, a feed carriage, and hydraulic actuating means for propelling said carriage, said hydraulic actuating means including a cylinder, a piston, a piston rod, and a crank, rotatable means connected to said carriage and driven by said crank and means adjustable along the length of said crank for connecting said piston rod to said crank, whereby the extent of feed may be adjusted by selective placement of said adjustable means on said crank.

2. In a machine of the character indicated, a feed carriage, longitudinally extending guide means for said carriage, feed means for said carriage, said feed means including a drum, cable means on said drum and connected to said carriage, hydraulic actuating means for driving said drum, ratchet means for one-way engagement between said hydraulic actuating means and said drum, and gear means connecting said hydraulic actuating means to said drum, said gear means including a pivoted member, a crank having an adjustable arm rotatably driving said pivoted member, and connecting means linking said hydraulic actuating means and the adjustable part of said arm.

3. In a machine of the character indicated, chucking means to receive internally fed stock, a feed carriage and elongated guide means therefor for feeding stock to said chucking means, chuck-actuating means for opening and for closing said chucking means, double-acting fluid-pressure-operated actuating means for feeding said carriage, a one-way-engaging connection between said fluid-pressure actuating means and said carriage, reversible fluid-pressure control means for reversibly operating said fluid-pressure-operated actuating means, and means interconnecting said fluid-pressure control means and said chuck-actuating means for changing the setting of said control means in response to an operation of said chucking means, the interconnection established by said last-defined means being such as to determine a first flow of pressure fluid to said fluid-pressure-operated actuating means in a feeding direction for a chuck-open position of said chuck-actuating means, such inter-connection further being such as to determine a second flow of pressure fluid to said fluid-pressure-operated actuating means in a reTRACTING direction for a chuck-closed position of said chuck-actuating means; whereby, in a single coordinated movement of said chuck-actuating means and of said fluid-pressure control means from one of said positions to the other, said chucking means may be opened and a length of stock fed; and whereby, in another single coordinated movement of said chuck-actuating means and of said fluid-pressure control means from the other of said control positions to the one, the stock may be chucked and said pressure-operated actuating means retracted.

4. A machine according to claim 3, and including feed means for said carriage and acting over and above said pressure-operated actuating means and constantly urging said carriage for propulsion in a feeding direction.

5. A machine according to claim 3, and including a drum, cable means around said drum and connected to said carriage at one end and weighted at the other end.

6. A machine according to claim 3, in which said pressure-operated actuating means for feeding said carriage includes a drum, cable means on said drum and connected to said carriage,

hydraulic actuating means for driving said drum, said one-way-engaging connection being between said hydraulic actuating means and said drum, and further one-way-engaging means between said drum and said frame.

7. A machine according to claim 3 in which said pressure-operated actuating means for feeding said carriage includes a drum, cable means on said drum and connected to said carriage, gear means for driving said drum, and hydraulic means for driving said gear means, said one-way-engaging connection being between said hydraulic actuating means and said drum, and said gear means including a longitudinally slidable rack connecting said hydraulic actuating means to said drum. 15
